HOT METAL CAR UNLOADING

John D. Pugh, deceased, late of Baltimore, Md., by
Addie A. Pugh, executrix, Baltimore, Md., as-
signor to Addie A. Pugh, Baltimore, Md.

Original application January 22, 1935, Serial No.
2,955. Divided and this application December
7, 1938, Serial No. 244,482

4 Claims. (Cl. 214—64)

The present invention relates to mobile containers for molten materials, generally designated "hot metal cars" and this application comprises a division of my Patent No. 2,144,637.

Mobile containers of the type made use of in the transportation of molten materials such as iron and steel from a point of origin in a steel plant to one or more points of destination, are now well-known and widely used. Such containers of the larger capacities are generally mounted upon wheeled trucks for transportation along suitable trackways and are provided with heavy insulating linings. Molten material introduced into such a car will not lose its heat rapidly during transportation but will remain in molten condition for long periods of time so as to be fluid when the car reaches its destination or discharging point. In my prior Patent No. 1,251,282, issued December 25, 1917, is described a form of mobile container or hot metal car, and the present car, while generally similar in its broader aspects to that disclosed in the aforementioned patent, includes a number of novel features which make it more useful for certain purposes.

An object of the invention is to provide a hot metal car which is so designed, and so supported, that its molten contents may be discharged in a novel manner, and by the use of novel and improved dumping or tilting means which is auxiliary to the container itself. Thus, in accordance with the present invention, the operator is enabled to discharge either the entire contents of the container by a continuous pouring operation, or any portion of such contents, the container being lifted bodily from its mobile supporting means and tilted upon auxiliary devices positioned adjacent the same, complete inversion of the container for cleaning purposes also being possible and the container being readily replaceable after such discharging operation, upon the mobile supporting means upon which it normally rests. In order that the container may be lifted bodily from its mobile support and manipulated for discharging purposes in the manner just described, the connections between the container and its supporting trucks are so designed that, while preventing relative bodily movement of the container for support in a horizontal plane under the influence of draft forces, disconnection of the container and supporting means is easily effected by the application of simple lifting forces to one side of the container body, and reconnection of the container to the mobile supports is automatically effected simply by the lowering of the container onto the supporting trucks.

In the embodiments of the present invention selected for disclosure by way of example, the hot metal car as an entirety is so constructed as to be movable along the trackway to a point of discharge, at which point of discharge the container body is positioned directly opposite certain toothed rack devices mounted alongside the trackway upon which the car moves. In some cases toothed racks so positioned with respect to the trackway may be moved toward the container body for engagement therewith and in other cases such devices are mounted in fixed position so as to be engageable by certain co-operating means on the container when the container is manipulated for dumping purposes, such manipulation being effected by the lateral movement of the container and its mobile supporting means on a section of the rails of the trackway mounted on rollers. Contact is made between the container and the toothed rack upon which it turns with the aid of a hook and cable depending from an overhead crane and in tilting or dumping movement the container body is moved along a curved path, upwardly and outwardly, until all portions thereof are entirely clear of the supporting trucks, the tilting movement of the container being continued to the desired extent. Any molten material or other substance which may be in the container is, of course, discharged when such tilting or inversion takes place and, if the container is completely inverted, its interior lining may be conveniently examined and cleaned if necessary.

To permit the elevation from and the return to the wheeled supporting trucks of the container body the connections between the container body and wheeled trucks are designed in a novel and improved manner, this novel connecting means being claimed in my Patent No. 2,144,637. These connections readily permit the desired movements of the container body independently of its supporting means while at the same time permitting, when the container is positioned upon its supporting means, free swiveling movement of the supporting trucks relatively to the container body and at the same time transmitting all draft forces from the trucks to the container body and vice versa, any draft forces imposed upon the car passing through the container body, in every instance the car being unprovided with any continuous underframe, such as generally used in hot metal cars of previous types.

The several embodiments of the invention selected for disclosure by way of example are il-

Illustrated in the accompanying drawing in which:

Figure 1 is a side elevation of a hot metal car embodying the novel features of the invention, a portion of one of the trucks being broken away to show connecting means between container and truck;

Figure 2 is an end view of a hot metal car, showing means for supporting the container body during discharging or dumping;

10 Figure 3 is a generally similar view but showing a modified form of the laterally positioned means for supporting the container body during dumping; and

15 Figure 4 is a transverse vertical section through a portion of the container and a portion of a supporting truck, showing the novel connecting means between container and truck.

The hot metal container illustrated in Figure 1 is of the large capacity type, being able to receive 20 and store a body of molten iron or steel weighing in the neighborhood of two hundred tons. It will be appreciated, however, that the actual size and capacity of the container may be varied as widely as desired and that the novel features of the 25 invention may be made use of in hot metal cars of all capacities.

The container of the hot metal car illustrated in Figure 1 is generally indicated at 10 and its shape is that of a form of revolution, with horizontal axis. Preferably it embodies a central cylindrical portion 11 and two frusto-conical end portions 12 rigidly attached to the central portion 11 and tapering toward the ends of the container body. The container ends 13 are conveniently formed as castings, rigidly secured to the outer ends of the frusto-conical sections 12. The container is lined with suitable insulating material and is provided with charging and discharging spouts 14, through which molten metal 40 or the like may be poured into the container and which permit the ready outflow of such material when the container is tilted.

The container body 10 is mounted directly upon supporting trucks 20, no interposed car platforms 45 or underframes being employed. In cars of large size, such as illustrated in Figure 1, each of the trucks 20 may have ten supporting wheels and may advantageously comprise a properly equalized and balanced consolidation of a six-wheeled truck 21 and a four-wheeled truck 22. Supported upon the trucks 21 and 22 is a super-bolster 35 which is shown partly in solid and partly in dotted lines in Figure 1. The outwardly projecting end portion 38 of the super-bolster 35 supports suitable draft mechanism, of which the coupler 39 comprises a portion.

The inner adjacent ends of the trucks are flexibly and adjustably connected together as by means of the two transversely extending curved 60 springs 40, bolted or otherwise connected together. This connecting and spacing means maintains the trucks in proper relationship to each other during the time that the container is removed therefrom, as hereinafter to be more fully described. By the use of the springs, or other equivalent flexible connection between the adjacent ends of the trucks, free articulation of the trucks when the car is passing around curves is permitted. The connecting means just described is of course not designed nor intended to transmit any portion of the draft forces, all of which forces 70 are transmitted through the container body 10.

The frusto-conical portions 12 of the container or ladle are provided with saddles 45 centrally 75 of which are formed the rounded king pins 46.

Upon either side of the king pin each saddle is provided with an upper side bearing portion 47, most clearly shown in Figure 4. Each of the super-bolsters 35 is provided with a socketed center bearing member 48 and side bearing portions 49 directly underlying the side bearing portions 47 of the saddle 45. Cylindrical rollers 50 are carried in suitable recesses formed in the side bearing portions 49 and are normally spaced slightly below the side bearing portions 47 of the saddle, at one end of the car. At the opposite end of the car the side bearings 47 are in contact with the rollers 50. This affords a substantially three-point suspension of the ladle on the two trucks and permits a certain flexibility or tilting of the relatively elongated car when rounding banked turns. This arrangement is only necessary in the case of exceptionally long cars having ladles or containers of large capacity. It will also be observed that, encircling each of the container ends 13, and rigidly secured thereto, is a toothed annulus or gear 12.

The car thus far described may be charged at any desired point and is freely movable along a trackway to any desired destination point, sometimes miles away from the charged point. In Figures 2 and 3 of the drawing is shown a car at a discharging point, the apparatus employed for assisting in the discharge of the container 10 being shown.

In Figure 2 of the drawing is illustrated a mechanism for cooperating with the container in unloading. In this form of the auxiliary unloading mechanism, extensible and retractable racks 70 are employed for engagement with the toothed rings 12 of the container. The toothed upper surfaces 71 of these racks, of which there are two arranged in parallelism, are preferably downwardly curved at the ends thereof closest to the trackway. The teeth of unloading racks 70 are, 40 when projected forwardly toward a hot metal car, adapted to engage and mesh with the teeth of toothed segments 72, rigid with the car. The racks are supported for substantial horizontal movements upon any suitable means, for instance, upon rollers 73 and 74, a horizontal flange 75 rigid with the outer end of each rack being supported for movement upon roller 73 and guided by the relatively small roller 76 positioned above the same. The forward edge of each rack 50 is provided with an inclined undersurface 77 which merges into a more steeply inclined undersurface 78 so that, as the rack is moved toward a container positioned as shown, its leading end will first be elevated slowly and thereafter 55 more quickly, with the end in view of moving its end radially of the container body to insure ready meshing of the rack teeth 71 with the segment teeth 72, any suitable driving means, not illustrated, being provided to effect such movement of the racks into container engaging position. The driving means may be connected to each rack by means of a link 78', slide block 79, and rotatable screw 80, having threaded engagement with block 79.

With the rack positioned as shown in full lines in Figure 2, and the teeth thereof in interlocking engagement with the teeth of segment 12 upon the container, it is obvious that a lifting force applied to the opposite side of the container 70 as by means of a crane hook 181, will effect movement of the container about the interengaging teeth of rack and segment and that the continued application of lifting forces will cause the container body to separate from the supporting 75

trucks and to roll along the parallel racks 70 into some such position as indicated in dotted lines in Figure 2, in which position the container is completely inverted. For partial dumping purposes, of course, the container may be moved to some intermediate position and of course suitable runners for hot metal and the like are provided for the reception of discharged material. The means connecting the supporting trucks and the 10 container body of the car illustrated in Figure 2 are formed in a manner analogous to that illustrated in Figure 4 so that disengagement of the body from the supporting trucks is readily effected and likewise reengagement of body and 15 trucks effected without difficulty.

In Figure 3 of the drawing is illustrated an unloading arrangement in which the unloading racks are fixed in position, instead of being movable toward and away from a fixed trackway. 20 Here the racks, one of which is indicated at 81, are mounted upon base members or pedestals one of which, indicated at 82, is partially illustrated. The rack teeth are indicated at 83 and it will be observed that the end of the rack which is adjacent the hot metal car is curved downwardly so that one or more of its teeth are disposed substantially radially to the axis of the container and positioned to readily intermesh with the radially extending teeth of the circular rack or segment 84 25 rigid with the container body. In order to effect engagement of the segments 84 and racks 81, the car as an entirety is moved laterally, the supporting rails 85 of the trackway being mounted upon rollers 86 which permit this lateral movement of 30 the track and hot metal car. Partial or complete discharge of the molten contents of the container may be effected by the application of lifting forces to the side of the container remote from the racks 35 81, as in the case of the forms of the invention previously described, the container body rolling upon the container supporting racks 81 to the desired discharging position, and being allowed to return by gravity, the means connecting the container and trucks readily permitting this manipulation of the container body as in the form of the 40 invention already described.

Obviously the means mounting the container body 45 upon the supporting trucks must be designed and constructed especially to permit the ready elevation of the container in the manner described and the ready return of the container to its original position upon the trucks. This connecting means has been described in detail and is shown in Figure 4.

It will be appreciated that the forms of the 50 dumping devices which are illustrated, and which have been described in detail, are set forth by way of example only and that the invention is applicable to still other forms of dumping devices. In 55 every instance, however, the means connecting the container body to the mobile supports will be so designed and constructed as to permit ready removal and replacement of the container body and associated with this means will be a container supporting mechanism adapted for lateral relative 60 movement with said container and upon which the

container may be rolled, or otherwise supported during a discharging operation. The discharging motion is brought about by the application of lifting forces to one side of the container body but the return motion is under the influence of gravity 5 although closely controlled by the operator. The use of power dumping appliances which form parts of the hot metal car itself is avoided and a container of maximum capacity for the weight of the car and the overall dimensions thereof is provided. 10

Having thus described the invention, what is claimed as new and desired to be secured by Letters Patent is:

1. The combination with a container for molten materials and a mobile support upon which the container rests, of means movable laterally of the container and its support into contact with the container when the support is at rest and upon which the container may be rolled after such contact is established, for the purpose of inverting the same. 15

2. The combination of a container shaped as a form of revolution and having two spaced circular series of external teeth disposed in planes 25 normal to its axis, a mobile support for said container from which the container may be lifted, and two toothed skids positioned in the planes of the container teeth, respectively, and movable toward the container until the teeth thereof are in meshing 30 relationship with the teeth of the container, said skids being adapted to serve as container supports and the container being adapted to be rolled onto said skids after the teeth 35 of the container have been brought into meshing relationship with the teeth of the container.

3. The combination with a container shaped as a form of revolution and having a plurality of spaced circular series of external teeth disposed in planes normal to its axis, a mobile support for 40 said container from which the container may be lifted, and a plurality of toothed skids positioned in the planes of the container teeth, respectively, and movable toward the container until the teeth thereof are in meshing relationship with the teeth 45 of the container, said skids being adapted to serve as container supports and the container being adapted to be rolled onto said skids after the teeth thereon have been brought into meshing relationship with the teeth of the container. 50

4. The combination with a container for molten materials and a mobile support upon which the container rests, of a toothed rack movable laterally of the container and its support into contact with the container when the support is at rest and 55 upon which the container may be rolled after such contact is established, for the purpose of inverting the same, and means supporting said toothed rack and comprising rollers engaging the lower surface thereof, a portion of said lower surface being inclined so as to cause a raising of the container-engaging end of said rack as said rack moves toward said container. 60
